UNITED STATES PATENT OFFICE.

ARTHUR COPELAND, OF WASHINGTON, DISTRICT OF COLUMBIA, ASSIGNOR
OF ONE-HALF TO MARTIN G. COPELAND, OF WASHINGTON, DISTRICT
OF COLUMBIA.

Fixture for Awnings, Curtains, and the Like.

No. 814,770.

Specification of Letters Patent.

Patented March 13, 1908.

Application filed April 18, 1903. Serial No. 153,168.

To all whom it may concern:

Be it known that I, ARTHUR COPELAND, a citizen of the United States, residing at Washington, District of Columbia, have invented 5 certain new and useful Improvements in Fixtures for Awnings, Curtains, or the Like; and I do hereby declare the following to be a full, clear, and exact description of the invention, such as will enable others skilled in the art to 10 to which it appertains to make and use the same.

My invention relates to fixtures for awnings, curtains, or the like which are attached to the material without puncturing the same.

The object of my improvement is to provide 15 inexpensive, strong, and durable fixtures for awnings, curtains, or the like whereby said fixtures may be securely attached to the material and the operation of putting up and taking down the awnings or curtains materially facilitated without sacrificing or weakening 20 the support for said awning or curtain.

My invention consists in features of novelty hereinafter fully described, and pointed out in the claims.

Reference will be made to the accompanying drawings to aid in the disclosure.

Figure 1 is a perspective view of an awning with my improved means for securing the same. Fig. 2 is a sectional view of the upper 30 edge of an awning, showing a face view of the fixture and the manner of supporting the fixture and attaching the same to the awning. Fig. 3 shows in detail a fixture applied to an awning before closing the fixture. Fig. 4 shows a similar view with the fixture and hook closed and ready for attaching to a proper support. Fig. 5 shows a modification 35 of my invention. Fig. 6 is a front view of my modified form of fixture supporting a curtain. Fig. 7 is an end view of the same. Fig. 8 is a detail view showing the fixture with a cord in place of the rod serving as a retaining means.

In my preferred form of the invention I 45 provide the upper edge of the awning, curtain, or the like with a hem or fold, which provides what I term a "pocket." In said pocket is placed, as at 7, a rod made of any suitable material or a cord. Said rod or cord 50 serves as a retaining means, as will be further described.

As a means for supporting my awning, curtain, or the like I use my improved fixture.

Said fixture consists of a tubular body portion 1 in the form of a collar or ring, although 55 the same may be of any other suitable contour. Said collar or ring has formed integral therewith a lug 2, which I have shown as perforated, forming an eye, although said lug may be made in the form of a hook. Dia- 60 metrally opposite said lug the collar or ring is slotted for the purpose hereinafter described. Formed exteriorly on said body portion and integral therewith is a hook 3. Said hook serves as a support for a sheave- 65 block which is used in folding up the awning. It is noted that said sheave-block may be omitted and the cord or rope run over said hook and also that a perforated lug may be used in place of the hook. 70

My fixture is preferably made of malleable iron, although the same may be made of any suitable material.

In assembling the parts of my awning the rod or cord is first placed in the pocket. Then 75 the fixture, which has an opening slightly larger in diameter than the combined diameter of the rod or cord and the fabric encircling the same, is passed over the upper edge of the awning. The slot in the body portion of the 80 fixture receives the body of the material supported as shown in Fig. 3. After said fixture is suitably adjusted on the awning the same is closed by pressure to bring the jaws 5 close against the body material. Sufficient 85 space is provided, however, between said jaws so as not to injure or puncture the material and at the same time to allow the body portion 1 to clamp the hem or folded portion tightly around the rod or cord, and the rod or 90 cord therefore serves as a retaining means, preventing the material from withdrawing from the fixture. The hook 3 is also closed against the body of the fixture, as shown in Fig. 4. 95

It will be noted that the interior of the fixture conforms to the configuration of the material and the retaining means, and therefore the fixture will embrace and clamp the material against the retaining means, which, as 100 above stated, is the rod or cord.

In Fig. 5 I have shown a slightly-modified form of fixture. This fixture is the same as the fixture shown in the other views, except the hook for the sheave-block has been omitted. Very often it is desired to support an 105

awning or curtain which is not to be folded, and in such instance the hook is unnecessary. I have also shown in this view a modified form of means for securing the material to the fixture. In this form the rod is slit longitudinally and the material inserted between the sections of the rod. The rod-sections are secured together by any suitable means. In order to better secure the material the opposing faces of the rod may be corrugated or roughened.

Figs. 6, 7, and 8 of the drawings show my modified form of fixture—that is, the fixture without the hook for a sheave-block—as supporting a curtain and a cord used as a retaining means to hold the curtain in the fixture.

While I have disclosed my invention as especially adapted for supporting awnings and curtains, I would have it understood that I contemplate using my improvement in other relations, such as for banners, flags, and the like. It is also to be understood that I do not wish to be limited to the precise details set forth, as they may be modified without departing from the principle of my invention.

What I claim as my invention, and desire to secure by Letters Patent, is—

1. A supporting-fixture for awnings, curtains or the like, consisting of a tubular body portion, having a longitudinal slot therein, means for supporting said body portion and means formed integral with and on the exterior surface of said body portion for supporting a sheave-block, said last-named means being independent of the supporting means, substantially as described.

2. A supporting-fixture for awnings, curtains or the like, consisting of a slotted ring or collar, a perforated lug carried thereby intermediate the ends thereof, and a hook on the exterior surface of said ring or collar, said hook being directly beneath said supporting-lug, substantially as described.

3. The combination of an awning, curtain or the like, having a hem or fold at its upper edge, a retaining means within said hem or fold, of supporting-fixtures therefor, each comprising a ring or collar having a slot par-

allel to its longitudinal axis, means for supporting the ring or collar and means carried by said ring or collar for supporting a sheave-block, said ring or collar being adapted to embrace and clamp the hem or fold around said retaining means, substantially as described.

4. The combination of an awning having a hem or fold at its upper edge, a retaining means within said hem or fold, of supporting-fixtures for said awning comprising a ring or collar having a slot parallel to its longitudinal axis, a perforated lug on the exterior portion of said ring or collar, diametrically opposite said slot and a hook carried by said ring intermediate the lug and slot, said ring or collar being adapted to embrace and clamp the hem or fold around said retaining means, substantially as described.

5. The combination of an awning, curtain or the like, having a fold therein, a retaining means within said fold, a supporting-fixture therefor independent of said retaining means and comprising a tubular body portion having a longitudinal slot therein, a perforated lug projecting from said body portion between its ends and having the axis of the perforation at substantially right angles to the axis of the tubular portion, a supporting-stud engaging the perforation whereby the fixture is freely supported, the slotted body portion embracing the fold and clamping the same about the retaining means and to the fixture, substantially as described.

6. A supporting-fixture for awnings, curtains or the like, consisting of a slotted ring or collar, a perforated lug carried thereby intermediate the ends thereof, and a hook on the exterior surface of said ring or collar, said hook being beneath said supporting-lug, substantially as described.

In testimony whereof I affix my signature in presence of two witnesses.

ARTHUR COPELAND.
